ATTORNEY

UNITED STATES PATENT OFFICE.

SHERWOOD HINDS, OF RICHMOND HEIGHTS, MISSOURI, ASSIGNOR TO ST. LOUIS PUMP & EQUIPMENT COMPANY, OF ST. LOUIS, MISSOURI, A CORPORATION OF MISSOURI.

MECHANICAL APPARATUS.

Application filed February 27, 1922. Serial No. 539,564.

This invention relates to mechanical apparatus, and with regard to certain more specific features, to measuring and non-measuring pumps for liquids.

5 Among the several objects of the invention may be noted the provision of a simple and inexpensive device for preventing unauthorized withdrawal of liquid by means of a pump; and the provision of compact and durable means for locking a storage tank. Other objects will be in part obvious and in part pointed out hereinafter.

10 The invention accordingly comprises the features of construction, combinations of elements, and arrangements of parts, which are exemplified in the construction hereinafter described and a scope of the application of which will be indicated in the following claims.

15 In the accompanying drawings, in which is shown one of various possible embodiments of this invention,

Fig. 1 is a front elevation,

Fig. 2 is a fragmentary left side elevation;

20 Fig. 3 is a vertical section on the line 3—3 of Fig. 1, on an enlarged scale; and

Fig. 4 is a view similar to Fig. 3 but showing the parts in unlocking position; for convenience of comparison with Fig. 3, the device is shown in Fig. 4 with the pipe vertical, whereas in practice it normally occupies a position inclined to the vertical when in unlocking position.

25 Similar reference characters indicate corresponding parts throughout the several views of the drawings.

30 Referring now more specifically to Fig. 1 of the accompanying drawings, there is illustrated a tank 1 for the storage of oil or other liquid. Mounted upon and extending into the tank 1 is a pump 3, here shown illustratively as adapted for operation by means of the hand crank 5.

35 The lock 7 for locking the pump, quantity handle 9 for determining the quantity of liquid to be delivered, and the meter or totalizer 11, are shown somewhat conventionally as they form no feature per se of the present invention.

40 During normal operation of the pump the liquid is discharged through the nozzle or other terminal 13.

Liquid is supplied to the tank through the

supply aperture 15 in the top of the tank. At this time the cover 17 is swung up about 45 its hinge 19.

Extending upwardly (Fig. 1) from the cover is a drip pipe or tube 21 having threaded to it at its upper end a lower joint member 23, upon which is pivotally mounted an 50 upper joint member 25. The latter member when in locked position (Figs. 1, 2 and 3) extends up into the apron or hood 27 or the terminal or nozzle 13. In this locked position, operation of the pump serves to discharge liquid through the nozzle, but the liquid merely passes down through the upper and lower joint members 25, 23 and pipe 21 back into the tank, and none of the liquid 55 can be obtained by the operator. The parts 60 may be retained in locked position by suitable means such as a padlock 29 (Fig. 1), serving to lock together the upper and lower joint members and to prevent relative movement of said members. The arrangement of 65 parts is such that the pipe and joint members cannot be swung as a whole about the cover hinge 19 as an axis because the hood 70 70 prevents movement of the upper joint member when the joint members are locked 75 together.

When the device is to be unlocked, the padlock 29 is first removed. Then the pipe is swung about the cover hinge as an axis, that is, rearwardly in Fig. 1 (counter-clockwise in Figs. 2 and 3). During such movement the upper joint member swings clockwise (Figs. 2 and 3) with respect to the pipe and lower joint member, thereby bringing the upper end of the upper joint member 90 down a little closer to the tank and permitting said upper end to pass out beneath the hood 27. The movement of the pipe counter-clockwise (Figs. 2 and 3) is preferably continued until the pipe rests in horizontal position, or at least near enough to the horizontal so that the cover is open far enough to receive any liquid that drips from the terminal or nozzle 13.

On the upper joint member is a hood or 100 apron 31 which in the locked position of the device extends down over the outer side of the upper edge 33 of the lower joint member. This apron 31, in connection with the hood 27, serves to make the device weatherproof 105 when in locked position.

The lower portion 35 of the outer wall of the upper member 25 is approximately coaxial with the pivot 37 between upper and lower members, and is nearer to the pivot than is the adjacent upper portion 33 of the outer wall of the lower member 23. Since in normal operation during unlocking the lower member swings counter-clockwise (Fig. 3) and the upper member swings 10 clockwise (Fig. 3) with respect to the lower member, any liquid that may be dripping from the upper member drips down into the lower member and is not wasted, as such liquid runs down through the pipe into the tank.

If it is desired to have the pipe 21 coaxial with the cover 17, the pipe may be bent for that purpose, or the shape of the lower member may be suitably modified to bring the 20 pipe into coaxial relation with the cover 17.

The device effectively prevents theft of liquid from the apparatus either through the aperture 15 in the tank or by operation of the pump, and since the cover 17 can- 25 not be raised when the device is locked, the single padlock 29 serves to protect against theft by way of the pump, thereby avoiding the necessity of having any lock on the cover 17 or pump.

30 The pivots 19 and 37 for cover and joint members respectively are so located with respect to the hood 27 of the nozzle as to prevent opening of the cover when the joint members are locked together and so as to 35 permit opening of the cover as above described when the joint members are not locked together. A preferred arrangement of the pivots and nozzle is shown in the accompanying drawings, wherein these three 40 points are approximately in the same straight line, as indicated in Fig. 2.

The pump may be of the measuring or non-measuring type.

From the above it will be seen that the 45 several objects of the invention are realized, and other advantageous results attained.

As various possible embodiments might be made of the above invention and various changes might be made in the embodiment 50 above set forth it is to be understood that all matter herein set forth or shown in the accompanying drawings is to be interpreted as illustrative and not in a limiting sense.

I claim:

55 1. In apparatus of the class described, in combination, a receptacle for the storage of liquid, a supply aperture therefor, a cover for said aperture, a pump adapted to discharge liquid from said receptacle, a nozzle on said pump through which said liquid is 60 discharged, the nozzle being located at a higher elevation than said aperture, a drip pipe extending up from the cover having a hinged portion adapted for engagement with said nozzle, said hinged portion swinging

vertically on a horizontal pin on said pipe, and means for locking the hinged portion of the pipe when said portion is engaged with said nozzle to prevent the cover from being opened, the pipe when in such locking position serving to convey back to the tank any liquid that is discharged from the nozzle.

2. In apparatus of the class described, in combination, a receptacle for the storage of liquid, a supply aperture therein, a hinged cover for said aperture, a pump adapted to draw liquid from the receptacle, a nozzle through which the liquid is discharged by the pump, the nozzle being located above the aperture so that liquid dripping from the nozzle when the cover is open drops directly through the aperture and back into the tank, a pipe extending through the cover and upwardly from the cover into the nozzle when the cover is closed, to receive the liquid from the nozzle, and jointed members, one mounted on the pipe and the other extending into the nozzle, the pivots of cover and joint members being so located with respect to the hood of the nozzle as to prevent opening of the cover when the joint members are locked and so as to permit opening when the joint members are unlocked.

3. In apparatus of the class described, in combination, a receptacle for the storage of liquid, a supply aperture therein, a hinged cover for said aperture, a pump adapted to draw liquid from the receptacle, a nozzle through which the liquid is discharged by the pump, the nozzle being located above the aperture so that liquid dripping from the nozzle when the cover is open drops directly through the aperture and back into the tank, a pipe extending through the cover and upwardly from the cover into the nozzle when the cover is closed, to receive the liquid from the nozzle, a lower joint member threaded on the pipe, an upper joint member pivoted thereto, a hood or apron on the nozzle into which the upper joint member extends, and means for locking the joint members against relative angular movement, the relative position of upper member and hood preventing opening of the cover when the joint members are thus locked, said joint members when unlocked having a relative angular movement as the cover is lifted, to permit the upper member to pass beneath and away from said hood.

4. In apparatus of the class described, in combination, a receptacle for the storage of liquid, a supply aperture therein, a hinged cover for said aperture, a pump adapted to draw liquid from the receptacle, a nozzle through which the liquid is discharged by the pump, the nozzle being located above the aperture so that liquid dripping from the nozzle when the cover is open drops directly through the aperture and back into the tank,

5 a pipe extending through the cover and upwardly from the cover into the nozzle when the cover is closed, to receive the liquid from the nozzle, a lower joint member threaded on the pipe, an upper joint member pivoted thereto, a hood or apron on the nozzle into which the upper joint member extends, and means for locking the joint members against relative angular movement, the relative position of upper member and hood preventing opening of the cover when the joint members are thus locked, said joint members when unlocked having a relative angular movement as the cover is lifted, to permit 10 the upper member to pass beneath and away from said hood; the upper member having a wall the lower portion of which is approximately concentric with said pivot and extending when in locked position down below 15 and within the adjacent wall of the lower member.

5. In apparatus of the class described, in combination, a receptacle for the storage of liquid, a supply aperture therein, a hinged 20 cover for said aperture, a pump adapted to draw liquid from the receptacle, a nozzle through which the liquid is discharged by the pump, the nozzle being located above the aperture so that liquid dripping from the nozzle when the cover is open drops directly through the aperture and back into the tank, a pipe extending through the cover and upwardly from the cover into the nozzle when the cover is closed, to receive the liquid from the nozzle, a lower joint member threaded on the pipe, an upper joint member pivoted thereto, a hood or apron on the nozzle into which the upper joint member extends, and means for locking the joint members against relative angular movement, the relative position of upper member and hood preventing opening of the cover when the joint members are thus locked, said joint members when unlocked having a relative angular movement as the cover is lifted, to permit 25 the upper member to pass beneath and away from said hood; the upper member having a wall the lower portion of which is approximately concentric with said pivot and extending when in locked position down below 30 and within the adjacent wall of the lower member, the upper member having a projection or hood extending when in locked position over the outside of the upper edge of the adjacent wall of the lower member, the 35 pivots of cover and joint members being so located with respect to the hood of the nozzle as to prevent opening of the cover when the joint members are locked and so as to permit opening when the joint members are unlocked.

position over the outside of the upper edge of the adjacent wall of the lower member. 50

6. In apparatus of the class described, in combination, a receptacle for the storage of liquid, a supply aperture therein, a hinged cover for said aperture, a pump mounted upon the receptacle and adapted to draw liquid from the receptacle, a nozzle through which the liquid is discharged by the pump, the nozzle being located above the aperture so that liquid dripping from the nozzle when the cover is open drops directly through the 55 aperture and back into the tank, a pipe extending through the cover and upwardly from the cover into the nozzle when the cover is closed, to receive the liquid from the nozzle, a lower joint member threaded on the pipe, an upper joint member pivoted thereto, a hood or apron on the nozzle into which the upper joint member extends, and means for locking the joint members against relative angular movement, the relative position of upper member and hood preventing opening of the cover when the joint members are thus locked, said joint members when unlocked having a relative angular movement as the cover is lifted, to permit 60 the upper member to pass beneath and away from said hood; the upper member having a wall the lower portion of which is approximately concentric with said pivot and extending when in locked position down below 65 and within the adjacent wall of the lower member, the upper member having a projection or hood extending when in locked position over the outside of the upper edge of the adjacent wall of the lower member, the 70 pivots of cover and joint members being so located with respect to the hood of the nozzle as to prevent opening of the cover when the joint members are locked and so as to permit opening when the joint members are unlocked.

In testimony whereof, I have signed my name to this specification this 25th day of February, 1922.

SHERWOOD HINDS.
